CLAIM

The ornamental design for a filter cartridge for clarifying, sterilizing or concentrating fluid feedstock, as shown and described.

DESCRIPTION

FIG. 1 is a perspective view showing a filter cartridge for clarifying, sterilizing or concentrating fluid feedstock showing our new design;

FIG. 2 is a side elevational view thereof, the other side being a mirror image;

FIG. 3 is a front elevational view thereof;

FIG. 4 is a rear elevational view thereof; and

FIG. 5 is a top plan view thereof, the rear view being a mirror image.

FIG. 2

FIG. 3

FIG. 4

FIG. 5
